[57] **CLAIM**

The ornamental design for combined portable fluorescent light and incandescent lantern, substantially as shown and described.

DESCRIPTION

FIG. 1 is a front perspective view from above of the combined portable fluorescent light and incandescent lantern of my invention;

FIG. 2 is a rear perspective view thereof from above;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and

FIG. 8 is an underneath plan view thereof.

The cylindrical diffuser is shaded with oblique lines to indicate a slight translucency, the light lines indicating fluting on the interior surface of the diffuser cylinder.

FIG. 1

FIG. 2

FIG. 3

FIG. 4

FIG. 7

FIG. 8
